UNITED STATES PATENT OFFICE.

JESSE THOMAS BENTHALL, OF SUFFOLK, VIRGINIA.

PISTON FOR INTERNAL-COMBUSTION ENGINES.

1,267,963.

Specification of Letters Patent. Patented May 28, 1918.

Application filed February 25, 1916. Serial No. 80,507.

To all whom it may concern:

Be it known that I, JESSE T. BENTHALL, a citizen of the United States, and a resident of Suffolk, in the county of Nansemond and State of Virginia, have invented a certain new and useful Improvement in Pistons for Internal-Combustion Engines, of which the following is a specification.

My invention relates to improvements in internal combustion engines, and it consists in the combinations, constructions, and arrangements herein described and claimed.

An object of my invention is to provide an improved piston for an internal combustion engine whereby an increase of power is obtained.

A further object of my invention is to provide an internal combustion engine having a piston capable of delivering more of the power of the explosive charge than a piston constructed in the ordinary manner, while at the same time not exceeding the ordinary piston in cost.

Other objects and advantages will appear in the following specification, and the novel features of the invention will be particularly pointed out in the appended claim.

My invention is illustrated in the accompanying drawings forming part of this application, in which—

Figure 1 is a sectional view through an engine and piston, constructed according to my invention, and

Fig. 2 is an enlarged sectional view through a portion of the device.

In carrying out my invention I may make use of a cylinder of any conventional form. In Fig. 1 I have shown such a cylinder 1 provided with an outer wall 2, the space 3 between the inner and outer walls being for the ordinary water jacket.

In the present instance, I have shown the piston as comprising a head portion 4 which forms the integral end of a cylinder 5. The piston has inwardly projecting lugs 6 which are bored as shown at 7 to receive a wrist pin 8. The pitman 9 has a portion 10 provided with a bearing 11 which surrounds the central portion of the wrist pin, and thus connects the piston to the pitman or connecting rod.

It will be observed that the outer surface of the head 4 is flat or plane, as shown at 4^a, while at 4^b there is a forwardly extending flange, having a concave curved portion

4^c on that side of the flange facing the plane surface 4^a.

The construction described provides a piston having a head, the greater portion of which is a plain flat surface, with outwardly curved edges, the curved portions being relatively near to the sides of the piston.

It is obviously desirable to concentrate as much as possible of the thrust of the exploding charge directly against the piston head. By constructing a piston in the manner described herein, the force of the explosion along the side walls is deflected away from the point of escape around the piston head and focused directly upon the piston head, thereby reducing the leakage around it.

Now I have found by actual experiment that a piston constructed in the manner described gives considerably more power than one which has merely a flat surface or a plane surface for the piston head.

I am well aware that the so-called dishing of the piston head is not new, and I do not claim such broadly; but I have found, by actual experiment, that a piston constructed in the manner described also gives more power than one with a dished or concaved head, w^hich advantage in performance I conceive to result from the following causes, to wit: that in the case of the flat surface, the force of the explosion is exerted in straight lines, as between the piston head and the cylinder head, along the entire diameter of the piston head, while in the case of the dished or concaved head, the force is partially deflected as between the piston head and the cylinder head, and to some extent expended in circumferential directions indirectly, thereby dissipating a part of the effective force.

But in a piston constructed in the manner described, the deflection is minimized to an insignificant fraction of the area of the piston head, while accomplishing a more effective concentration of the force of the explosion against it, as well as deflecting the thrust along the walls away from the point of escape around the piston head. Furthermore, by constructing a piston head in the manner described herein, I have the advantage of a relatively small absorption of heat which is attained by making the main body portion of the head flat or plane. At the same time, I attain the advantage of the dished piston by forming the curved

portion at the very place where it is needed, to wit, toward the edge of the piston, this curved portion being entirely sufficient to accomplish the results of the ordinary 5 dished piston without, however, causing an extra amount of surface, which would, therefore, absorb more heat. In actual 10 practice I have tried out pistons with plane surfaces, and those with the so-called dished surfaces, that is to say, with a recess of 15 convex cross section extending substantially over the whole of the end of the piston. In each instance I have found that the engine under the same conditions gives less power than when the piston is constructed in accordance with my invention.

It will be seen at once that I have accomplished a new result without increasing the 20 cost of the piston. The piston head may be cast to a shape approximating that of the piston when finished, and a finishing tool may be run over the cast head so as to give the finish required.

The piston is provided with the usual 25 packing rings 12. In this connection I wish to mention also that, a piston constructed in accordance with my invention tends to prevent, to a certain extent, the forcing of the 30 products of combustion past the side walls of the piston. The deposit of carbon upon the side walls is, therefore, eliminated to a certain extent, while at the same time the

advantages of the flat piston head are also retained.

The relatively narrow flange, 4^b, is a 35 continuous and unbroken circle and projects a relatively short distance beyond the flat surface, 4^a, and the inner concave surface of the flange as shown at 4^c, extends on a continuous concave line from the upper 40 edge of the flange to the base, where it merges into the flat surface, 4^a. By thus forming the flange, a strong and rigid continuation of the effective surface of the piston is provided, which is not liable to undue 45 expansion, and thus the increase of frictional contact between the outer surface of the flange and the wall of the chamber is obviated.

I claim:—

A piston for internal combustion engines, having a flat surface facing the combustion chamber, and a relatively narrow continuous integral rigid flange surrounding the flat surface and projecting therefrom at 55 the outer edge, the inner surface of said flange formed on a continuous concave curve beginning at its upper edge and merging at its base into the flat surface, whereby the currents of the expanding and eddying 60 gases are directed by such inner curved surface away from the space between the piston and cylinder wall.

JESSE THOMAS BENTHALL.
